Int. Cl. D27—03
U.S. Cl. D85—2

FIG. 1

FIG. 3

FIG. 2

FIG. 1 is a side elevational view of an ash tray, showing my new design;

FIG. 2 is a top plan view; and

FIG. 3 is a cross-sectional view thereof, taken on line 3—3 in FIG. 2.

This is a continuation-in-part of design application, Ser. No. D. 6,282, filed Mar. 20, 1967, which was in turn a continuation-in-part of design application Ser. No. D. 2,090, filed May 2, 1966, both now abandoned.

I claim:

The ornamental design for an ash tray, as shown and described.
